INTERNAL SPACER BAR CONNECTOR FOR A METAL CABINET

Eric Harry Lewer, Thorney Weir, Iver, Buckinghamshire, England, assignor to Alfred Imhof Limited, London, England, a company of Great Britain

Filed July 1, 1959, Ser. No. 56,616

Term of patent 14 years

(Cl. D54—1)

FIG. 1 is a rear perspective view of an internal spacer bar connector for metal cabinet showing my new design; FIG. 2 is a front perspective view taken from above thereof;

FIG. 3 is a top plan view thereof; and

FIG. 4 is a rear elevational view thereof.

The spacer bar connector is symmetrical, the configuration being the same on both sides of the central V-shaped web shown in FIGS. 2 and 3.

The connector is characterized by the centrally disposed generally V-shaped web member as best shown in FIGS. 2 and 3.

I claim:

The ornamental design for an internal spacer bar connector for a metal cabinet, as shown and described.
